UNITED STATES PATENT OFFICE.

IGNAZIO SANFILIPPO, OF CASTELTERMINI, ITALY

ORE-ROASTING FURNACE.

No. 820,138.

Specification of Letters Patent.

Patented May 8, 1906.

Application filed September 10, 1903. Serial No. 172,541.

To all whom it may concern:

Be it known that I, IGNAZIO SANFILIPPO, civil engineer, a subject of the King of Italy, residing at Casteltermini, Sicily, Italy, have 5 invented certain new and useful Improvements in or Relating to Ore-Roasting Furnaces, (for which I have applied for Letters Patent of Italy on July 8, 1903,) of which the following is a specification.

10 This invention relates to certain new and useful improvements in ore-roasting furnaces; and it has for its objects, among others, to provide an improved device of this character in which the furnace is provided with two 15 divided and superposed compartments for a purpose which will hereinafter appear. I aim also at other improvements, which will also be further described.

15 The further objects and advantages of the invention will hereinafter appear, and the novel features thereof will be specifically defined by the appended claims.

20 The invention is clearly illustrated in the accompanying drawings, which, with the letters of reference marked thereon, form a part 25 of this specification, and in which—

Figure 1 is a vertical section of one form of my improved furnace. Fig. 2 is a similar view of a slightly-modified form thereof.

30 Like letters of reference indicate like parts in the different views.

Referring to the drawings, *a* designates the hopper or mouth through which the ore is charged into the upper compartment. The 35 furnace may be of any desired form. In Fig. 1 I have shown it as terminated at the top by a flat ceiling or top supported on pillars, while in Fig. 2 it is represented as having a cupola or vaulted ceiling, the filling-opening in each 40 case being in said top or ceiling. The character of the top, however, does not affect the operation of the device and may be changed as may be desired.

45 *m* designates the upper compartment, and *n* the lower compartment. The lower compartment *n* is surmounted by hollow pillars *i*, supported by suitable means in the lower compartment, as shown, and these pillars are provided with transverse openings *s*, as seen in

50 both views, which openings extend to the upper ends of the pillars and to the top of the upper compartment *m*. The pillars are formed with longitudinal cavities for a purpose which will soon be made apparent. The 55 said pillars facilitate the free passage and circulation of the hot gases. According to the

nature of the ores under treatment the hot gases are to traverse the bulk of the ores from the top downward, entering through the inlet *h* and being discharged through a flue *e* in the 60 direction of the arrows—as, for instance, in the sulfurous ores—or vice versa—as, for instance, in the treatment of metallic ores, where the hot gases are to enter from beneath and discharge at the top. Such circulation 65 of the gases through the interior of the hollow transversely-perforated pillars could not take place if the said pillars were mounted directly on the bottom of the furnace. I therefore provide under the ore-containing chamber *m* 70 the free compartment *n*, communicating with the internal cavities of the pillars.

The bottom of the upper compartment is inclined, as shown, and at the lower end of this incline is the outlet *f*.

75

l is a closure of any suitable character.

e is a conduit leading from the compartment *n* out through the top of the furnace, while *h* is a chimney or conduit leading into the high side of the ore-compartment *m*.

80

The furnace above described is especially adapted for the metallurgical treatment of different ores, but most especially for the treatment of crude sulfur ores and the refinement of sulfur. The ore is charged into the 85 furnace through the upper mouth or hopper *a* and distributed in the free spaces between the pillars *i*. The quantity of the ore charged into the furnace is such as to leave uncovered the upper ends of the hollow transversely- 90 perforated pillars. Thereupon the opening *a* of the furnace is closed, when the hot gases of the flue *h*, through the holes *s* of the pillars left uncovered at the upper end of the latter, enter the hollow interior of the pillars, thus 95 heating the mass of the crushed ore in the chamber *a*, and pass to the inferior chamber *n*, whence they leave the furnace through the flue *a*. The sulfur liquefied by the action of the hot gases by means of the holes and cavities of the hollow pillars pours into the compartment *n* and is collected through the discharge *f*. When the operation is finished, the closure *l* is demolished in order to clean 100 out the furnace.

105 In operation in the treatment of sulfur ores, when it is desired to obtain sulfur by liquefaction due to combustion to a part of the ore, and in the analogous treatments, the gaseous currents are fed by the conduit *h* into the upper end of the upper compartment *m* along the longitudinal cavities of the pillars in the

direction of the arrows and escaping through the conduit *e*, leading from the lower compartment *n*. In the treatment of a different character, where the heating must be from the bottom upward, the gaseous currents should be given a direction of flow the reverse of that above described.

It is to be noted that the two compartments *m* and *n* when the furnace is working communicate only by the interior longitudinal cavities of the pillars with each other or through the transverse openings or by openings that may be provided in the horizontal partition between the two compartments, which partition may be supported in any suitable manner in the lower compartment *n*.

A furnace constructed as above described insures the regular and complete heating of the ore being treated.

20. What is claimed as new is—

1. In an ore-roasting furnace, two divided and superposed compartments and hollow pillars extending from the lower through the upper compartment and perforated throughout their length.

2. In an ore-roasting furnace, two divided and superposed compartments, and hollow pillars extending from the lower through the upper compartment and having transverse openings at the top of the upper compartment.

3. In an ore-roasting furnace, two divided and superposed compartments; hollow pillars

extending from the lower through the upper compartment and perforated throughout 35 their length, and means for introducing gaseous currents to the upper compartment.

4. In an ore-roasting furnace, two divided and superposed compartments, hollow pillars extending from the lower compartment and 40 through the upper, and having transverse openings, and means for introducing gaseous currents into the upper compartment and discharging the same through the lower compartment.

5. In an ore-roasting furnace, two divided and superposed compartments, and hollow pillars extending upward through the compartment containing the ore to be treated and perforated throughout their entire length. 50

6. In an ore-roasting furnace, an upper and a lower compartment the former containing the ores to be treated, and hollow transversely-perforated pillars traversing the same from top to bottom, and an under compartment communicating with the hollows of the said pillars and means for introducing gaseous currents into the upper compartment and discharging the same through the lower compartment.

In witness whereof I have hereunto set my signature in the presence of two witnesses.

IGNAZIO SANFILIPPO.
